UNITED STATES PATENT OFFICE.

ISAAC N. WILLIAMS, OF FOLTZ, INDIANA.

GATE.

No. 876,122.

Specification of Letters Patent.

Patented Jan. 7, 1908.

Application filed March 23, 1907. Serial No. 364,186.

To all whom it may concern:

Be it known that I, ISAAC N. WILLIAMS, a citizen of the United States, residing at Foltz, in the county of Jefferson and State 5 of Indiana, have invented a new and useful Gate, of which the following is a specification.

The invention relates to improvements in gates.

10 The object of the present invention is to improve the construction of gates, and to provide a simple and inexpensive gate, which will be light, strong and durable, and which may be readily adjusted to counter-act sagging.

With these and other objects in view, the invention consists in the construction and novel combination of parts hereinafter fully described, illustrated in the accompanying 20 drawing, and pointed out in the claims here- to appended; it being understood that various changes in the form, proportion, size and minor details of construction, within the scope of the claims, may be resorted to with- 25 out departing from the spirit or sacrificing any of the advantages of the invention.

In the drawing:—Figure 1 is a side elevation of a gate, constructed in accordance with this invention. Fig. 2 is a similar view 30 partly in section. Fig. 3 is a detail sectional view, illustrating the construction of the clip for clamping the inclined braces together.

Like numerals of reference designate cor- 35 responding parts in all the figures of the drawing.

1 and 2 designate vertical end bars, which may be constructed of any suitable material, such as wood, angle iron, or tubular metal, and to which is secured wire netting or 40 fencing 3, or other woven wire, which con- stitutes the body of the gate. The connect- ing wires are stapled, or otherwise secured to the vertical end bars 1 and 2, which are connected by extensible inclined braces 4, 45 constructed of tubular metal and having flattened ends 5, which are secured by suit- able fastening devices 6 to the end bar 1 of the gate. The end bar 1 is provided at its upper and lower portions with slots or bi- 50 furcations 7 to receive the flattened ends 5

of the inclined braces, which are diagonally arranged and which cross each other at the center of the gate. The other ends 8 of the inclined braces receive threaded rods or screws 9, which have flattened outer ends 55 10, secured by suitable fastening devices 11 in slots or bifurcations 12 of the end bar 2 of the gate.

The tubular braces are diagonally ar- 60 ranged and extend from the corners of the gate at one end thereof to within a short distance of the corners at the other end of the gate. The screws or threaded rods 9 and the tubular braces form telescopic members, and the former receive nuts 13, which engage the 65 ends 8 of the tubular braces and which are adapted to extend the diagonal braces for stretching the connecting wires to the de- sired tension. The extensible diagonal braces are adapted to maintain the connect- 70 ing wires at a high tension, and they may be adjusted from time to time to counter-act sagging.

After the diagonal braces have been prop- 75 erly adjusted, they are secured together at the point of crossing by a substantially U-shaped clip 14, receiving the tubular braces and provided with a clip plate 15, which is retained on the sides of the clip by means of nuts 16. The terminals of the 80 sides of the U-shaped clip are threaded to receive the nuts 16.

The fastening devices 6 and 10 constitute pivots and permit the necessary oscillatory movement of the extensible diagonal braces, 85 incident to the stretching of the flexible body portion of the gate.

Having thus fully described my invention, what I claim as new and desire to secure by Letters Patent, is:—

1. A gate comprising end bars, a flexible body portion connecting the end bars, diagonally arranged tubular braces connected to one of the end bars, adjusting means connect- 95 ing the said braces with the other end bar and adapted to extend the said braces for stretching the flexible body portion of the gate, and a centrally arranged clip receiving and clamping the tubular braces.

2. A gate comprising end bars, a flexible 100

body portion connecting the end bars, and inclined diagonally arranged bracing means composed of telescopic members and connected with the end bars, adjusting devices for extending the bracing means, and means for clamping the diagonally arranged bracing means at the point of crossing.

In testimony, that I claim the foregoing as my own, I have hereto affixed my signature in the presence of two witnesses.

ISAAC N. WILLIAMS.
